CLAIM

The ornamental design for an aerosol generation device as shown and described.

DESCRIPTION

FIG. 1 is a top, front perspective view of an aerosol generation device showing our new design;

FIG. 2 is a bottom, rear perspective view of the aerosol generation device of FIG. 1;

FIG. 3 is a top, rear perspective view of the aerosol generation device of FIG. 1;

FIG. 4 is a front view of the aerosol generation device of FIG. 1;

FIG. 5 is a rear view of the aerosol generation device of FIG. 1;

FIG. 6 is a right side view of the aerosol generation device of FIG. 1;

FIG. 7 is a left side view of the aerosol generation device of FIG. 1;

FIG. 8 is a top view of the aerosol generation device of FIG. 1;

FIG. 9 is a bottom view of the aerosol generation device of FIG. 1; and,

FIG. 10 is a top, front perspective view of the aerosol generation device of FIG. 1.

The broken lines in the drawings depict portions of the aerosol generation device that form no parts of the claimed

(Continued)

design. The dot-dash-dot broken lines in the drawings represent boundaries of the design and form no part thereof.

1 Claim, 10 Drawing Sheets
